UNITED STATES PATENT OFFICE

VINCENT SCHULIS, OF CHICAGO, ILLINOIS, ASSIGNOR, BY MESNE ASSIGNMENTS, TO INDUSTRIAL PATENTS CORPORATION, OF CHICAGO, ILLINOIS, A CORPORATION OF ILLINOIS

BRINE RETAINING AND DISCHARGE VALVE MECHANISM

Application filed February 22, 1928. Serial No. 256,450.

This invention pertains to the general class of devices adapted for use with cooling apparatus of a refrigerator car and particularly to a brine valve mechanism therefor. An object of applicant's invention is the production of a brine valve and means for operating same that are simple in construction, of a small number of parts, positive in operation, readily installed, economical to manufacture and fool-proof. A further object of applicant's invention is the production of a brine valve mechanism by means of which a quick discharge of the brine may be effected. A further object of applicant's invention is the production of a brine valve mechanism which operates in a manner to prevent dampening of the felt insulation within the car, corrosion of the under-frame, and dripping along the tracks. A further object is the production of a device of this character which will not readily become clogged and is easily opened should any obstruction occur. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a transverse vertical section through a refrigerator car.

Fig. 2 is an elevation of the upper end of the operating rod and parts adjacent thereto;

Fig. 3 is a sectional elevation through the valve body;

Fig. 4 is a perspective view of the operating rod guide bracket;

Fig. 5 is a sectional plan view taken on line 5-5 of Fig. 1 and through the valve body and tank nipples; and

Fig. 6 is a section on line 6-6 of Fig. 5.

Referring now to the drawings, in Fig. 1, 1 shows a refrigerator car having a plurality of ice tanks 2, 3, 4 and 5 arranged in pairs on each side of the car. Tanks 2 and 3 have a

common brine valve mechanism 6 and tanks 4 and 5 have a common brine valve mechanism 7. The mechanisms 6 and 7 are duplicates, the first being shown with the operating rod 8 in open position and the second with the operating rod 8 in closed position. In addition to the operating rod 8, each brine valve mechanism comprises a valve body 9, a pipe 10, tank nipples 11 and 12 connected to tanks 2 and 3 respectively, hose connections 13, 14 and 15, a discharge pipe line 16, and an operating rod guide bracket 17.

The interior of the valve body is shown in Fig. 3. Pipe 10 is shown connected to the upper portion thereof by means of a flanged member 18 which is internally threaded at 19 to accommodate the pipe 10. Operating rod 8 extends upward through the pipe 10 and has attached to the bottom thereof a tapered plunger 20 which in the preferred embodiment is of cast iron. The plunger 20 is preferably threaded on to the rod 8 or otherwise suitably secured thereto, and has preferably secured to the bottom thereof a beveled rubber valve washer 21 which is locked on the operating rod 8 together with the tapered plunger 20 by means of a washer 22 and a burr 23. This valve washer is preferably formed with a double bevel on its edge as shown. The tapered plunger is preferably formed with a portion of uniform diameter 24 and the tapered portion 25. The shape of the tapered portion 25 is such as to conform to the tapered seat 26 of the valve body 9. The rubber washer 21 is preferably of a size such that its beveled edge will engage the conical seat 26 first, thus holding the conical portion 25 of the plunger away from the seat, only allowing same to engage when the rubber washer is worn or otherwise displaced. The conical portion 25 thus comes into actual contact with the seat only in case of an emergency, same under normal conditions wedging the tip 21' of the valve washer against the seat 26. At each side of the valve body 9 are the hollow projections 27 and 28 over which fit the hose connections 13 and 14 respectively.

Hose connections 13 and 14 also connect to tank nipples 11 and 12 respectively. The tank nipples are shown more clearly in Figs. 5 100

and 6. The tank nipples 11 and 12 are provided with tubular portions 29 and 30 over which the hose connections 13 and 14 fit. Each tank nipple is provided with flanges 31 and 32 respectively which engage tanks 2 and 3 respectively. Tanks 2 and 3 are shown round at their bottom portions. However, it is obvious that the tanks may be of any desired shape, the tank nipples 11 and 12 being shaped to conform therewith. Tank 2 is provided with an aperture 33 and tank 3 with an aperture 34 through which mounts 35 and 36 of nipples 11 and 12 respectively project. It will be noted that each mouth is provided with a guard portion 37 which extends downward below the channel 38 of the nipple. Nipple 11 is used as an illustration in Fig. 6. The purpose of this construction is to prevent chips and sticks of wood and other foreign matter floating on top of the brine from passing through the channel 38 and into the valve body 9. Tank nipples 11 and 12 may be secured to their respective tanks in any suitable manner such as with solder or with bolts 25 or any other suitable means. The valve discharges outward through the pipe line 16 which is connected to the valve body by means of the hose connection 15. Pipe line 16 is bent preferably at 37' and extends downward through the bottom of the car as shown at 38' and is preferably provided with an additional angular portion 39 in order that the brine when discharged will not come in contact with the underface of the car.

35 The pipe 10 at its top is secured to an extension 40 on the operating rod guide hanger bracket 17 preferably by means of wire bands 41 and 42 passing around the pipe 10 and the extension 40 and secured in place by the fingers 43 stamped or otherwise formed at the bottom of the extension 40. The operating rod guide bracket has preferably a base portion 44 to which the extension 40 is attached and side wings 45 and 46 which pass between the members of the center bridging 47. The side wings 45 and 46 have outwardly and downwardly extending angular portions 48 and 49 respectively which hook over the members of the center bridging 47. The operating rod 8 is provided with an offset portion 50 and a handle portion 51. The wings 45 and 46 with their angular top portions constitute spaced hanger members for engaging frame members of the car to suspend and firmly support the tubular guide therefrom, and this supporting of the tubular guide and the valve from the frame members of the car will relieve the hose connections 13 and 14 of strain incident to the weight of the tubular member and to vibration resulting from train motion. The angular downwardly extending portions 48 and 49 form substantially hook-shaped portions for engaging the frame members of a car, and the space between the hanger members guides the upper portion

of the operating rod and will prevent rotary movement of the same when the valve is in its closed position.

The operation of the device is as follows: After removing the hatch plug, the operating rod 8 is raised by means of its handle 51 and is turned so that the offset portion 50 rests upon the center bridging 47. In this position the plunger 20 and the rubber washer 21 are disengaged from the seat 26 of the valve body 9 and the valve is open. The operating rod is left in this position until the brine has ceased to flow. The operating rod is then turned to its original position and the weight of the rod will return the rubber washer 21 and the plunger 20 to their original closed position. In this position the tip 21' of the beveled portion is wedged between the conical portion 25 of the plunger and the seat 26. Fresh ice is then placed in the tanks. Of course it is understood that other forms of valve washers may be used.

It will be noted that with applicant's novel construction the valve member cannot be left open after icing, inasmuch as the handle 51 projects upward when the valve is in the open position to such an extent as to prevent replacing of the hatch plug. The pipe 10 not only serves as a guide for the operating rod 8 but is also a standpipe whereby a head is always maintained on the outlet in the valve body, same being of sufficient height to prevent water flowing over the top thereof.

With applicant's novel construction the tanks in the car can be drained within three or four minutes, thus effecting a great saving of time. Should the valve become clogged, same is readily cleaned by means of removing the rod 8. However, clogging of the valve is prevented not only by the novel mouth for the nipples, but also by the smooth contour of the valve seat, there being no shoulders on same.

The ordinary pans which are installed in refrigerator cars are not used except for the collection of sweat from the tanks, thus clogging of same is avoided inasmuch as no sediment settles in same. All sediment from the brine tanks is carried out directly through applicant's novel valve mechanism.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described, a valve body having a valve seat, a vertical tubular guide connected at its lower end with the valve body, a combined hanger and guide bracket composed of spaced hanger portions

provided with means for engaging frame members of a car, the space between the hanger members forming a guide, means for connecting the upper end of the tubular guide 5 with the said bracket, a valve plunger within the valve body cooperating with the valve seat, and an operating rod connected with and carrying the valve plunger and extending through and guided by the tubular member 10 and the space between the hanger members.

2. In a device of the class described, a valve body having a valve seat, a vertical tubular guide connected at its lower end with the 15 valve body, a combined hanger and guide bracket composed of spaced hanger members provided at the top with substantially hook shaped portions for engaging frame members of a car, the space between the hanger members forming a guide, and a base portion connecting the hanger members of the bracket, means for connecting the tubular member with the base portion of the bracket, a valve plunger within the valve body 20 operating with the valve seat, and an operating rod connected with and carrying the valve plunger and extending through and guided by the tubular member and the space between the hanger members of the bracket.

25 3. In a device of the class described, a valve body having a valve seat, a vertical tubular guide connected at its lower end with the valve body, a combined hanger and guide bracket composed of spaced hanger portions 30 provided with means for engaging frame members of a car, the space between the hanger members forming a guide, means for connecting the upper end of the tubular guide with the said bracket, a valve plunger within 35 the valve body cooperating with the valve seat, and an operating rod connected with and carrying the valve plunger and extending through and guided by the tubular guide and the space between the hanger members 40 and having a handle at its upper end and provided at a point below the handle and spaced therefrom with means for engaging the bracket at the top thereof for holding the valve in its open position and the handle in 45 a projecting position.

50 In testimony whereof, I have hereunto signed my name.

VINCENT SCHULIS.
